NIGHTSHIRT OR THE LIKE

Peter Skendrovic, R.D. 5, Box 197, Irwin, Pa.

Filed Sept. 19, 1961, Ser. No. 66,748

Term of patent 14 years

(Cl. D3—26)

Fig. 1

Fig. 2

FIGURE 1 shows a front elevational view of the nightshirt;

FIGURE 2 shows a rear elevational view of the nightshirt.

The characteristic feature of my design for a nightshirt resides in the combination of a plaid fabric skirt having a sporran resembling patch pocket combined with a plain fabric buttonless top, all as shown.

I claim:

The ornamental design for a nightshirt or the like, as shown and described.
